UNITED STATES PATENT OFFICE.

JACOB FELBEL, OF NEW YORK, N. Y., AND CARL GABRIELSON, OF GREENVILLE, NEW JERSEY; SAID GABRIELSON ASSIGNOR TO SAID FELBEL.

TYPE-WRITING MACHINE.

SPECIFICATION forming part of Letters Patent No. 687,500, dated November 26, 1901.

Application filed April 26, 1901. Serial No. 57,519. (No model.)

To all whom it may concern:

Be it known that we, JACOB FELBEL, of the borough of Manhattan, in the city, county, and State of New York, and CARL GABRIELSON, of Greenville, in the county of Hudson and State of New Jersey, citizens of the United States, have invented certain new and useful Improvements in Type-Writing Machines, of which the following is a specification.

10 Our invention relates more particularly to front-strike writing-machines of the general construction shown in the patent granted to Jacob Felbel September 18, 1900, No. 657,927, and the patent granted to Carl Gabrielson 15 February 26, 1901, No. 668,713, although some of the features are applicable to other types of machines.

The objects of the invention are to improve the above-referred-to machines, to minimize 20 the liability of binding or cramping the key-levers and to improve the mounting thereof, to improve the key-lever springs, to improve the type-bar-shifting mechanism, to improve the mounting of the universal bar, and to effect various other improvements in the machine, all as will hereinafter appear.

The invention consists in certain combinations of devices, features of construction, and arrangements of parts, all as will be hereinafter fully set forth, and particularly pointed out in the concluding claims.

In the accompanying drawings, Figure 1 is a central vertical section taken longitudinally of a front-strike machine made in accordance with our invention, all of the parts being shown in normal position. Fig. 2 is a perspective view of a portion of the mechanism for shifting and locking the type-bars. Fig. 3 is a top plan view of the lower portion 40 of the machine. Fig. 4 is a front sectional elevation of the machine, taken just forward of the type-bar segment. Fig. 5 is a perspective view illustrating the manner of mounting the key-lever springs. Fig. 6 is a detail of some of the parts of the case-shifting mechanism. Fig. 7 illustrates the working position of the case-shift lock. Fig. 8 is one of a pair of brackets which support both the universal bar and the sublever fulcrum-rod. 45 Fig. 9 is a front sectional elevation of the lower portion of the machine, taken just for-

wardly of the universal-bar frame. Fig. 10 is a bottom plan view.

In the several views portions are omitted or broken away, so as to disclose the several improvements more clearly, and similar parts are designated by similar numerals of reference.

The framework of the machine comprises a base 1, corner-posts 2 thereon, and a top plate 3, over which travels a platen 4. Rearwardly-striking radial type-bars 5 are pivoted at their rear ends upon a curved wire 6, which is seated in a curved groove 7, formed in a segment 8, the latter being radially slotted at 9 65 to receive the type-bar hubs. Each type-block 10 bears two characters. At their forward ends the type-bars rest upon a pad 11, fitted in a case 12, which is supported by horizontal rods 13, whose rear ends are fixed in 70 the segment-casting. For each type-bar is provided a returning-spring 14, attached to a hook 15, pivoted to the type-bar hub and extending obliquely therefrom, the forward end of the spring being attached to one of a series 75 of fingers 16, formed upon a segmental plate 17, secured to the pad-case 12.

The type-bars are connected by rearwardly-extending links 18 to the upper ends of upright bell-crank 19, the lower portions whereof are pivoted at 20 upon horizontal key-levers 21, between the ends of the latter. The bell-crank or sublevers cross the key-levers and are provided therebeneath with forwardly-extending arms having horizontal 85 slots 22, which fork a fixed horizontal transverse fulcrum-bar 23, antifriction-rollers 24, Fig. 3, being disposed along said bar. Depression of the key-levers causes the upwardly-extending arms 19 to vibrate rearwardly about the pivots 20 and swing the type-bars up to print. Keys 25 are provided upon the forward ends of the levers 21, whose rear ends bear up against the under surface of a flat horizontal fulcrum-plate 26. The 90 rear ends of the levers are formed with elongated convexly-curved obliquely-extending treads 27, the forward portions of the treads normally bearing up against said fulcrum-plate. During the vibration of a lever the 95 point of contact thereof with the fulcrum-plate creeps rearwardly, and at the comple-

tion of the stroke the rear end of the tread is bearing. Thus at the beginning of the stroke the key is enabled to have a good leverage or purchase upon the type-bar, while during the stroke said leverage is automatically decreased, reaching a minimum at the completion of the stroke. The treads are notched to engage a fixed horizontal transverse rod 28, whereby endwise displacement of the levers is prevented, and are guided in a fixed comb 29, whose slots are open at the top, the solid portion or back of the comb extending across beneath the key-levers and being secured by forwardly-bent ears 30 and screws 31 to the bottom edges of a pair of fixed parallel bars 32, between which the rear ends or treads of the key-levers are arranged. Said bars are provided with ears 32^a, which are screwed to bosses 33, formed upon the under side of an overhanging plate portion 1^a of the base. Midway between its ends the comb 29 is provided with a forwardly-extending keeper-ear 34, which is screwed to the bottom of a lug 35, depending from the plate 1^a, said ear overlapping or extending beneath the rod 28, whose middle portion is supported in a notch in said lug, and the latter extending down between the middle key-levers, which are separated, so as to afford room therefor.

The ends of the fulcrum-plate 26 rest upon the top edges of plates 36, secured by screws 37 to the opposing faces of the bars 32, said edges being shaped to coincide with the key-lever treads 27, so that the fulcrum-plate may be tipped upon said edges or ways while in contact with the key-levers and without disturbing the latter. By adjusting the fulcrum-plate it may be caused to contact with the key-lever treads at other points, thereby altering the initial leverage of the keys upon the type-bars. By this means the initial key resistance may be increased and the key-stroke shortened, since the more the rear portion of the fulcrum-plate is tipped downwardly the greater the initial distance between the bearing-point and load-point of the lever and the sooner is the leverage of the key reduced to the minimum. The adjustment of the plate is effected by a thumb-screw 38, which is threaded through the overhanging portion 1^a of the base and contacts at its lower end with the upper face of the fulcrum-plate, a headed shoulder-screw 39 passing up through a perforation 40 in the latter and being tapped into the lower end of the thumb-screw, so that the plate may be adjusted either downwardly or upwardly by turning the thumb-screw in the proper direction. At each end of the fulcrum-plate and upon its upper face is fixed a plate-spring 41, whose forward end bears up against the under side of the overhanging plate 1^a and serves to hold the fulcrum-plate down upon its ways, so that it cannot yield when the keys are operated.

Referring now to Fig. 3, it will be noted that the key-levers diverge or fan out from their rear ends to the keyboard. The width of the key-lever system at the junction of the sublever system therewith is substantially 70 equal to the width of the type-bar system or to the system of links 18, the bell-crank 19 extending vertically from the key-levers to the links. The width of the key-lever system at said junction of the sublever system is 75 greater than the width of the rear end of the levers and less than the width at the keyboard. Beginning at a point just forward of the sublever system the divergence of the key-levers increases or the levers fan out 80 more rapidly than at their rear ends, while the key ends of the key-levers—that is, the portions thereof which extend in front of the usual comb 42—are parallel. It will be seen that the key-levers work in diverging vertical 85 planes, but that the load-point and tread or fulcrum end of each lever lie substantially within the vertical plane in which the lever works, so that there is a direct application of power, side strain or torsion of the lever being avoided, and binding or cramping of the latter in its guiding-comb being minimized or eliminated. It will be seen at Fig. 3 that if a line (representing a vertical plane) be drawn directly from the rear end of any key-lever to 90 the center of its key it will pass through or, at least, very close to the load-point of the lever where the sublever 19 is pivoted, and it will also be seen that the tread of the lever substantially coincides with said line, and 95 hence works at all times in the same vertical plane, so that binding or cramping is avoided at all portions of the lever-stroke. It will further be seen that the sublevers 19 vibrate rearwardly and forwardly in diverging vertical 100 planes, according to the divergence of their respective key-levers.

Arranged over the key-levers is a set of horizontal wire-loop or duplex springs 43, the rear ends of which are mounted upon a transverse 105 horizontal bar 44, Figs. 1, 3, 5, and 10, whose ends are secured by screws 45 upon the forward ends of the fixed bars 32. Upon the rear edge of the bar 44 are formed teeth 46, beneath which the closed ends of the loops 110 are hooked, the loops passing thence upwardly and being bent over the rear corner of the bar, whence they extend forwardly beyond the sublevers 19, the forward ends of the springs being bent at 47 and engaging open 115 vertical hooks 48, whose lower ends are pivoted to the key-levers, each branch of each spring being thus connected to a separate lever. It will be seen that the springs which bear upon the top of the bar 44 extend longitudinally of the key-levers and are sufficiently long to be very elastic and also that they may be readily engaged or disengaged from the teeth 46 and hooks or links 48. The latter swing freely upon their pivots during the 120 movements of the key-levers. The key-levers are of assorted lengths, and, as will be seen at Fig. 5, one branch of each loop-spring 125 is longer than the other, the longer branch

being connected to a long lever bearing a key in one of the two forward rows at the keyboard and the shorter branch being connected to a shorter lever bearing a key in one of the two rear rows, thus in a measure equalizing the resistance of the keys to the finger touch. Over the rear portions of the springs extends a cover-plate 49, which is fastened by screws 50 upon the bar 44 and has along its rear side a downwardly-directed keeper-flange 51, which lies against the teeth 46 and prevents accidental displacement of the springs.

The type-bar segment or frame 8, which is capable of vertical shifting movements, is guided by antifriction-balls 52, running in vertical grooves formed both in the sides of the frame and also in guide-posts 53, which are secured by screws 54 upon seats 55, Fig. 4, cast upon the base 1. By mounting the segment-guides upon the base instead of upon the top plate, as shown in said patents, not only is considerable jar and noise eliminated during the shifting of the segment, but it becomes possible to remove the top plate, together with the ribbon and carriage mechanisms usually placed thereon, for repairing or adjusting these mechanisms and without disturbing the type-actions, while at the same time ready access is afforded to said type-actions for cleaning, repairing, or adjusting the same. Moreover, the type-actions may be completely assembled before the top plate is put on, which is a great desideratum and effects a considerable economy in manufacture. The segment-frame is connected by downwardly-extending links 56 to a pair of rocker-arms 57, extending rearwardly from a rock-shaft 58, the latter crossing the base and being journaled in the side walls thereof and being also provided with an adjustable spring 59 for opposing the weight of the segment and type-bars and rendering the latter easier to elevate. Upon the rock-shaft 58, near its left-hand end, is fixed a forwardly-extending rocker arm or lever 60, which cooperates with a lever 61, arranged by the side thereof and loosely engaging the shaft by means of a hub 62. Said lever 61 has an elongated curved tread 61^a, upon which bears the bottom edge of a lever 63, which is provided at its forward end with a shift-key 64. The tread 61^a inclines downwardly from its front end, which is first engaged by the lever 63, and as the latter is depressed the contact-point between the two levers creeps gradually toward the lever-axis 58. Thus the shift-key has a good initial purchase upon the shifting mass, so that the latter is easily put in motion, while the leverage decreases during the stroke, so that the shift is effected without an excessive dip of the key.

The shifting movements of the segment-frame are limited by stop-arms 65, fixed upon the guide-posts 53, with which coact adjustable stops 66, provided upon the frame. When said stops are adjusted, the position of the rocker-arm 60, which is positively connected

to the segment-frame, is changed, as well as the position of the lever 61, and in order to adjust the latter to its normal position with reference to the shift-key lever 63 a slot 67 is formed longitudinally of said lever 61, and there is arranged therein an eccentric-disk 68, which is perforated to receive the shank of a large-headed screw 69, which is tapped into the forward end of the rocker-arm 60. The eccentric may be swung upon the axis 69, so as to adjust the lever 61 into contact with the key-lever 63, and then the screw 69 may be tightened, so as to clamp the eccentric against the face of the rocker-arm 60, said eccentric being thicker than the lever 61, so that the head of the screw may not touch the latter and bind thereon. The lever 61 is provided with a looped guiding-strip 70, open at its upper end and forking the shift-lever 63, so as to prevent the latter from working off from the tread 61^a. The lever 63 is pivoted at its rear end upon a pin 71, fixed in a lug 72, depending from the base-plate 1^a, and an extended end of the lever carries a compression-spring 73, which bears on the under side of the plate 1^a for returning the lever to normal position. A segment shifting and locking lever 74, pivoted upon the pin 71 and arranged alongside of the principal shift-lever 63, bears upon an anti-friction-roller 75, mounted upon the lever 61, and is provided with a key 76 and a returning-spring 77. Upon the upper edge of the lever rests a gravity-latch 78, which is mounted upon a pivot-screw 79 and provided with a jog 80, the latter being adapted to engage the head 81 of an adjustable screw, which is tapped into an upwardly and forwardly extending arm 82, formed upon the hub 83 of the rocker-arm 60, said screw being provided with a binding-nut 84. The arm 82 is ranged alongside of the locking key-lever 74 and beneath the latch 78, the forward end of the latter being bent inwardly at 78^a, so as to rest upon the top of the lever 74, whereby it is supported in normal position. The lever 61 and the shift mechanism controlled thereby may be operated by either of the key-levers 63 and 74, the latter being used, however, only when it is desired to permit the latch 78 to drop into engagement with the adjustable stop 81 upon the arm 82, so as to prevent the return to normal position of said arm, and hence of the entire shifting mechanism. When the parts are in the Fig. 7 position, the friction between the jog or shoulder 80 and the screw 81 is sufficient to prevent the spring 77 from vibrating the key-lever 74 upwardly and lifting the latch 78. Hence by the depression of the key 76 the type-segment is both shifted and locked.

Extending transversely beneath the key-levers is a universal bar or roller 85, which is journaled upon the rear ends of arms 86, secured by hubs 87 upon a rock-shaft 88, the latter being mounted upon pivots 89, secured by screws 90 in a bracket 91, which is fastened by screws 92, Fig. 9, to the under side

of a horizontal bar 93, extending across the open base and cast integral therewith. It will be seen that the universal-bar shaft is arranged just forwardly of the sublever fulcrum-rod 23 and that the latter is also secured to the brackets 91, Fig. 8, by keepers 94 and screws 95. An arm 96 extends rearwardly from the rock-shaft 88 and is connected by a vertical link 97 to a rocker 98, which is provided with both a feeding-dog 99 and a detent-dog 100, coöperating with a rack 101 in the usual manner to control the letter-feeding movements of the platen 4. Said dog-rocker is provided with a returning-spring 102. The arm 96 upon the universal-bar shaft is extended forwardly at 103 and provided with a compression-spring 104, which bears up against the under side of a curved arm 105, secured by a screw 106 to the under side of the bar 93, about midway of its length, and hooking over the fulcrum-rod 23, so as to afford a support therefor and prevent vibration of the middle portion thereof at the operation of the sublevers 19. The link 97 is slipped over a pin 107, projecting laterally from the arm 96, and is held in place by a yielding keeper 108, the forward end of which is riveted to the arm 96.

In operation a type-key 25 is depressed, forcing down the lever 21, together with the sublever or bell-crank 19, pivoted thereon, the latter being caused by the fulcrum-rod 23 to swing rearwardly at its upper end and through the link 18 to pull the type-bar up to print. At the same time the universal bar 85 is carried down, thus rocking the shaft 88 and by means of the arm 96 and link 97 operating the dog-rocker 98, so as to disengage the feeding-dog 99 and engage the detent-dog 100 with the rack 101. Upon the relief of the finger-key from pressure the springs 14, 43, 102, and 104 return the parts to normal position, the rack 101 and platen 4 being fed a letter-space in the usual manner. During the printing stroke of the key-lever the tread 27 thereon rolls along or upon the fulcrum-plate 26, thus gradually decreasing the leverage of the key upon the type-bar, and hence gradually increasing the key resistance and checking the movement of the operator's hand, so as to avoid giving a jar thereto at the completion of the stroke. Simultaneously the speed of the type-bar is increased, so that a sharp blow is delivered thereby. At the beginning of the return stroke the leverage of the key upon the type-bar is least, and hence the movement of the latter is made at maximum speed, so that it is not likely to collide with the next-operated type-bar. If it is desired to increase the key resistance and diminish the dip thereof, the screw 38 may be adjusted downwardly, thereby tipping the fulcrum-plate 26 upon its ways 36, the rear portion of said plate descending, whereby the initial contact or bearing point of all of the levers is shifted rearwardly, thereby decreasing the initial leverage of the

keys upon the type-bars, and hence increasing the key resistance and shortening the key-stroke, as already explained. It will be seen that, if desired, the screw 38 may be turned down until only the extreme rear bearing-points of the lever-treads touch said plate, thereby reducing the key-stroke to a minimum. The springs 41 keep the plate 26 constantly bearing upon its ways, so that there is no shake of the former in any position. When it is desired to print a capital letter, the shift-key 64 is depressed, forcing down its lever 63 and the lever 61, thus rocking the shaft 58 and swinging upwardly the arms 57 thereon and by means of the links 56 elevating the segment-frame, type-bars, and type-basket. While the type system is in this position, any of the type-keys 25 may be operated, thereby causing the capital or upper-case types upon the type-blocks 10 to print. The upward shift of the type system is assisted by the spring 59, and the touch of the shift-key is further improved because of the great initial leverage of the shift-key lever 63 upon the lever 61, whereby the initial resistance of the key to the touch is diminished. Upon the release of the key 64 the type system drops to normal position. When it is desired to write several words in capital letters, the shift and lock key 76 is depressed, and through its lever 74 and the roller 75 the lever 61 is forced down, thus elevating the type-segment in the above-described manner, said lever 61 acting through the rocker-arm 60 to rock the shaft 83, and the arm 82 simultaneously swinging forwardly, as illustrated at Fig. 7. During the downward movement of the lever 74 the latch 78 is permitted to drop, and at the time that the shift movement of the type-segment is completed said latch falls behind the head of the screw 81 upon said arm 82, thereby locking the latter against return movement and also holding down the locking-key lever 74, since the spring 77 is incapable of causing the lever 74 to rise against the frictional opposition arising from the reaction of the arm 82 upon the projection 80 of the pawl. Thus both hands of the operator are left free to manipulate the type-keys. When it is desired to return the type-segment to normal position, the principal shift-key lever 63 is depressed, and by bearing down the lever 61 the pressure between the screw 81 and the projection 80 of the latch 78 is relieved, so that the spring 77 is enabled to lift both the lever 74 and the latch, thus unlocking the arm 82, and hence permitting the type-segment to drop.

What we claim as new, and desire to secure by Letters Patent, is—

1. In a type-writing machine, the combination of a system of type-bars, a system of key-levers extending beneath the type-bars, and a system of connections extending upwardly from the key-levers to the type-bars, the width of the system of connections being less

than the width of the keyboard, and the key-levers being parallel at their key ends and converging from the keyboard to their rear ends and working in converging vertical planes.

2. In a type-writing machine, the combination of a system of type-bars, a system of key-levers extending beneath the type-bars, and a system of connections extending upwardly from the key-levers to the type-bars, the width of the system of connections being less than the width of the keyboard, and the key-levers being parallel only at the keyboard and converging therefrom to a line just forward of the connections, and thence converging less sharply to their rear ends, so that the fulcrum load-point and key of each lever lie substantially in line.

3. In a type-writing machine, the combination of a system of type-bars, a system of converging key-levers, and a system of levers pivoted upon the converging portions of said key-levers and connected to the type-bars.

4. In a front-strike writing-machine, the combination of a system of rearwardly-striking type-bars, a system of converging key-levers, a system of bell-crank pivoted upon the converging portions of said key-levers and vibrating in converging planes, and a fulcrum-bar extending transversely beneath the key-levers, said bell-crank having upwardly-extending arms which are connected to the type-bars and also having arms engaging said fulcrum-bar.

5. In a front-strike writing-machine, the combination of a system of rearwardly-striking type-bars, a system of converging key-levers extending rearwardly beneath the type-bars and having extended treads which are adapted to work along a fixed fulcrum-plate so as to change the leverage of the keys upon the type-bars, a system of bell-crank pivoted upon the levers and working in converging vertical planes, and a fulcrum-bar extending transversely beneath the key-levers and engaged to forwardly-extending arms upon the bell-crank, the latter also having upwardly-extending arms which are linked to the type-bars.

6. In a type-writing machine, the combination of a series of type-bars, a series of levers connected to the type-bars and having converging elongated treads, an adjustable fulcrum-plate along which said treads work, and a guide-comb for the tread portions of the levers, said guide-comb being fixed upon the framing.

7. In a type-writing machine, the combination of a series of type-bars, a series of levers connected to the type-bars and having elongated converging treads, an adjustable fulcrum along which said treads work, and a guide-comb for the tread portions of the levers, said guide-comb being fixed upon the framing and the guiding-slots in said comb being open at the top.

8. In a type-writing machine, the combina-

tion of a series of type-bars, a series of key-levers of the second order connected thereto and having converging treads at their rear ends, an adjustable fulcrum-plate along which said treads work, fixed bars 32 between which said treads are confined, and a slotted comb having guiding-slots open at the top and secured at its ends upon said bars. 70

9. In a type-writing machine, the combination of a series of type-bars, a series of key-levers connected thereto and having converging treads 27, transverse guiding-comb 29 extending beneath said treads, parallel bars 32 80 to which said comb is secured by ears 30, ears 32^a whereby said bars are secured to the framing, and fixed rod 28 engaging notches formed in the treads.

10. In a type-writing machine, the combination of a series of type-bars, a series of key-levers connected thereto and having converging treads 27, transverse guiding-comb 29 extending beneath said treads, parallel bars 32 to which said comb is secured by ears 30, ears 90 32^a whereby said bars are secured to the framing, and fixed rod 28 engaging notches formed in the treads, said comb having between its ends an ear 34 which is attached to the framing and overlaps the middle portion of the 95 rod 28.

11. In a type-writing machine, the combination of a series of type-bars, a series of key-levers connected thereto and having converging treads 27, transverse guiding-comb 29 extending beneath said treads, parallel bars 32 to which said comb is secured by ears 30, ears 100 32^a upon said bars whereby they are secured to the framing, and fixed rod 28 engaging notches formed in the treads, said comb having between its ends an ear 34 which overlaps the middle portion of the rod 28 and is secured to a lug 35 along each side of which key-levers are ranged, said rod 28 being seated in a notch formed in said lug. 105

12. In a type-writing machine, the combination of a system of type-bars, a system of key-levers of the second order connected thereto and having converging curved treads, a base having a plate portion 1^a which overhangs said treads, a guide-comb 29 extending beneath the treads and having guiding-slots open at their upper ends and engaging the converging treads, ears 30 and 34 upon said comb, transverse rod 28 engaging notches in 115 said treads, fixed at its ends in the base, seated between its ends in lug 35 depending from said overhanging portion 1^a, and held in said notch by said ear 34, bars 32 attached to the under side of said base portion 1^a, said 120 ears 30 being secured to said bars, bearing-plates 36 secured upon said bars, a fulcrum-plate resting upon said bearing-plates 36, a thumb-screw 38 for adjusting said fulcrum-plate, screw 39 passing through a perforation in said fulcrum-plate and tapped into said thumb-screw, and springs 41 fixed upon said fulcrum and bearing up against the under side of said overhanging portion 1^a. 125 130

13. In a type-writing machine, the combination with a set of type-operating key-levers, of a bar extending transversely over said levers and having teeth upon its rear edge, a set of loop-springs detachably hooked upon said teeth and extending forwardly, and links connecting the forward ends of said springs to the key-levers. 75
14. In a type-writing machine, the combination of a set of type-operating levers, a bar extending transversely thereof, a series of teeth upon said bar, a series of loop-springs caught upon said teeth and extending longitudinally of the levers and connected thereto, and a keeper plate or bar for said springs. 80
15. In a type-writing machine, the combination of a set of type-bars, a set of key-levers connected thereto, transverse bar 44 having teeth 46, loop-springs 43 hooked upon said teeth, links 48 connecting said springs to the key-levers, and cover-plate 49 having a keeper-flange 51 which is placed over said springs. 85
16. In a front-strike writing-machine, the combination of a set of type-bars, a set of key-levers extending rearwardly beneath the type-bars and having treads at their rear ends, a plate along which said treads work, a system of sublevers pivoted upon said key-levers and connected to the type-bars, and a system of forwardly-projecting springs mounted in rear of said sublevers and connected to the key-levers in front of said sublevers. 90
17. In a front-strike writing-machine, the combination of type-bars 5, key-levers 21 having treads 27, fulcrum-plate 26, upwardly-extending sublevers 19 pivoted upon the key-levers and connected to the type-bars, springs 43 mounted in rear of the sublevers and projecting forwardly beyond the sublevers, and links 48 connecting said springs at their forward ends to the key-levers. 95
18. In a type-writing machine, the combination with a set of type-operating key-levers of assorted lengths, of a transverse bar, teeth upon said bar, and loop-springs hooked upon said teeth and connected to said key-levers, the branches of each loop being of unequal length and connected to key-levers of unequal length. 100
19. In a front-strike writing-machine, the combination of a base, a set of type-bars, a frame in which said type-bars are mounted, vertical grooves formed in the sides of said frame, guide-posts secured at their lower ends upon the base of the machine at the sides of said frame and unsecured at their upper ends, opposing grooves formed in said guide-posts, bearing-balls running in said grooves, means for shifting said frame, and keys connected to said type-bars. 105
20. In a front-strike writing-machine having a base, corner-posts thereon, and a top plate attached to the corner-posts, the combination of a set of rearwardly-striking type-bars, a frame upon which the latter are piv- 110
- otally mounted, grooves formed in the sides of said frame, grooved guides extending upwardly from the base at each side of said frame and unattached at their upper ends, balls working in said grooves, a shift-key connected to said frame, and a set of key-levers mounted in the base and connected to said type-bars. 115
21. In a type-writing machine having a base and a top plate supported thereover, the combination of a set of type-bars, a frame upon which they are mounted, guide-posts at each side of said frame, seats 55 upon the base to which said guide-posts are secured, and a set of key-levers mounted in the base and connected to said type-bars. 120
22. In a front-strike writing-machine having a base, the combination of a set of type-bars, a frame in which they are mounted, a pair of guiding devices extending upwardly from the base of the machine at the sides of said frame and unattached at their upper ends, stops upon said guiding devices, corresponding stops upon said frame, and a set of keys mounted in the base of the machine and connected to said type-bars. 125
23. In a type-writing machine, the combination of a set of type-bars, a shiftable frame upon which they are mounted, a rock-shaft operatively connected to said frame, arm 60 mounted upon said shaft, lever 61 having tread 61^a, eccentric 68, screw 69, slot 67 in said lever 61, and shift-key lever 63 bearing 130 upon said tread. 135
24. In a type-writing machine, the combination with a set of type-bars, and a shiftable segment upon which they are mounted, of an arm 82 operatively connected to said segment, an adjustable device 81 thereon, a latch 78 adapted to engage said adjustable device, and a key-lever 74 connected to said segment and holding said latch in an idle position. 140
25. In a type-writing machine, the combination of a set of type-bars, a shiftable segment in which they are mounted, rock-shaft 58 connected to said segment, arm 82 upon said rock-shaft, adjustable screw 81 upon said arm, pivoted latch 78 having shoulder 80 for 145 engaging said screw 81, key-lever 74 holding said latch in an inoperative position, and means for enabling said key-lever to rock said shaft. 150
26. In a front-strike writing-machine, the combination of a set of type-bars, a vertically-shifting segment in which they are mounted, rock-shaft 58 connected to said segment, arm 60 upon said rock-shaft, lever 61 having tread 61^a, eccentric 68, screw 69, slot 67, shift-key 155 lever 63 bearing upon said tread, arm 82, adjustable screw 81 upon said arm 82, latch 78 having a portion 80 for engaging said screw 81, lever 74 holding said latch in an inoperative position, and roller 75 mounted upon 160 said lever 61 for engagement by said lever 74. 165
27. In a type-writing machine, the combination with a set of type-operating levers, of a transverse universal bar or roller 85, arms

86 upon the ends of which said roller is journaled, rock-shaft 88 to which said arms are secured, pivots 89 upon which said rock-shaft is mounted, brackets 91, a fixed transverse horizontal bar 93 to which said brackets are secured, and carriage-feeding devices operated by said universal bar.

28. In a front-strike writing-machine, the combination of a set of type-bars, a set of key-levers, a set of sublevers pivoted upon the key-levers and connected to the type-bars, a fulcrum-rod 23 forked by said sublevers, brackets 91, keepers 94, and screws 95.

29. In a type-writing machine having a base, the combination of a set of type-bars, a set of key-levers, a set of sublevers pivoted upon the key-levers and connected to the type-bars, a bar 93 extending across the base, brackets 91 secured to said bar, pivots 89 in said brackets, shaft 88 mounted upon said pivots, arms 86 upon said shaft, universal bar 85 carried by said arms and connected to carriage-feeding devices, fulcrum-rod 23 carried in said brackets 91 and detachably retained by keep-

ers 94, said rod 23 being forked by said sublevers, and arm 105 extending from said bar 93 and engaging the middle portion of said fulcrum-rod 23.

30. In a type-writing machine having a base, the combination of a set of type-bars, a set of key-levers, a set of sublevers pivoted upon the key-levers and connected to the type-bars, a bar 93 extending across the base, brackets 91 secured to said bar, fulcrum-rod 23 carried in said brackets 91 and retained by detachable keepers 94, said rod 23 being forked by said sublevers, and arm 105 extending from said bar 93 and engaging the middle portion of said fulcrum-rod 23.

Signed at the borough of Manhattan, city of New York, in the county of New York and State of New York, this 25th day of April, A. D. 1901.

JACOB FELBEL.
CARL GABRIELSON.
